[57] CLAIM

The ornamental design for a fishing seat, as shown and described.

DESCRIPTION

FIG. 1 is a perspective view of a fishing seat, showing our new design, taken from a forward portion thereof;

FIG. 2 is another perspective view, taken from a reward portion thereof;

FIG. 3 is a front elevational view;

FIG. 4 is a top plan view;

FIG. 5 is a right-hand side elevational view, wherein the left-hand side elevational view is substantially identical;

FIG. 6 is a rear elevational view; and,

FIG. 7 is a bottom plan view thereof.
